US00D353296S

United States Patent [19]

Assmann

[11] **Patent Number:** Des. 353,296[45] **Date of Patent:** ** Dec. 13, 1994[54] **ESPRESSO MACHINE WITH SPHERIC
DISPENSING HEAD**

4,760,774 8/1988 Lin ..... D9/309 X

[75] **Inventor:** Jürgen Assmann, Essen, Germany**OTHER PUBLICATIONS**[73] **Assignee:** WIK
Elektro-Hausgeräte-Vertriebsgesell-
schaft GmbH & Co.
Produktions-Kommanditgesellschaft,
GermanyEspresso Machine (top right), Form 117, Jan. 1987 p.
52.[**] **Term:** 14 Years*Primary Examiner*—Alan P. Douglas
Assistant Examiner—Marianne N. Pandozzi
Attorney, Agent, or Firm—Sixbey, Friedman, Leedom &
Ferguson[21] **Appl. No.:** 1,687**[57] CLAIM**[22] **Filed:** Nov. 20, 1992The ornamental design of an espresso machine with
spheric dispensing head, as shown and described.[30] **Foreign Application Priority Data****DESCRIPTION**

May 22, 1992 [DE] Germany M9203832.8

FIG. 1 is a frontal perspective view showing the new
design of the present invention;[52] **U.S. Cl.** ..... D7/309; D7/311FIG. 2 is a rear perspective view showing the new
design of the present invention;[58] **Field of Search** D7/300, 305, 309, 310,
D7/311, 306, 307, 308; 99/279FIG. 3 is a top plan view showing the new design of the
present invention;[56] **References Cited**FIG. 4 is a side perspective view showing the new
design of the present invention from the right side rela-
tive to the view of FIG. 1; and,**U.S. PATENT DOCUMENTS**FIG. 5 is a side perspective view showing the new
design of the present invention from the left side rela-
tive to the view of FIG. 1.
